UNITED STATES PATENT OFFICE.

WILLIAM S. THAYER, OF OWEGO, NEW YORK, ASSIGNOR OF ONE-HALF TO
CHARLES M. HAYWOOD, OF SAME PLACE.

BOLTLESS RAILWAY-JOINT.

SPECIFICATION forming part of Letters Patent No. 319,641, dated June 9, 1885.

Application filed February 14, 1885. (No model.)

To all whom it may concern:

Be it known that I, WILLIAM S. THAYER, a citizen of the United States, residing at Owego, in the county of Tioga and State of New York, have invented certain new and useful Improvements in Boltless Railway-Joints; and I do hereby declare that the following is a full, clear, and exact description of the same, reference being had to the annexed drawings, making a part of this specification, and to the letters and figures of reference marked thereon.

This invention is an improvement in railroad-rail joints, and has for an object to provide a simple construction by which to securely fasten the rails to a track-bed, and in such manner that any one rail may be removed at will without disturbing the adjacent ones.

To this end the invention consists in certain novel constructions and combinations of parts, which will be hereinafter first fully described, and then pointed out in the claim.

In the drawings, Figure 1 is a perspective view of a section of a track having my improvements. Fig. 2 is a transverse section drawn through the rail and chair. Fig. 3 is a transverse section drawn through the rail and key. Fig. 4 is a detail view of the chair. Fig. 5 is a detail view of the key, and Fig. 6 is a longitudinal section cut through the chair and key.

In carrying out my invention I provide the meeting ends of the rails A A with slots B B', which coincide when the rails are joined. The chair C is formed with the two side plates, D D, and an intermediate horizontal rib, E. The side plates, D D, are conformed at their upper portions to the web of the rail, and have their lower portions adapted to the base of the rail, beyond which they extend, as shown in Fig. 2, and are provided in their outer ends with bolt-holes for the fastening-spikes. It will be seen that the chair is so formed with reference to the rails that its side plates fit snugly into the hollow of the rail and against both sides thereof in such manner as to prevent all lateral vibration or movement of the ends of the rail, either jointly or independently. It will be noticed that the slot B' is made sufficiently long in

one end of the rail to wholly receive the rib of the chair, so that when such chair is moved back into such slot it will free the short slot B, and the joint will be released. When desired to remove a rail from between others, it is only necessary to unspike the chair and key at the two joints, remove the key, then adjust such chair into the longer slot of each joint, when the rail, on being unspiked, may be removed without disturbing either of the adjacent rails, as will be seen, whereas if the chair fully filled the slots in the ends of the rails one or the other of the adjacent rails would have to be removed before the intermediate one could be raised. The key F is formed with a head, G, and a shank, H. The shank H is adapted to be inserted through the slot B' in rear of the chair, and to fill such slot in the adjustment of parts. (Shown in Fig. 6.) The head of this key holds the key from movement through the slot, as will be understood from Fig. 3. I adapt the lower side of the shank to the base of the rail, beyond which it extends, and has a spike-opening, as shown. The upper side of the shank is conformed to that of the lower portions of sides D of the chair, so that the meeting portions of the chair and key will coincide and no shoulders be formed between them. It is preferred to use the key, because it operates to completely fill the long slot B', and in connection with the chair locks the rails, thus preventing the creeping of the rails frequently experienced in the use of the common fastenings. Also, by bolting this key to the track I provide an additional security against any lateral movement of the rails. A plate, I, is placed underneath the rail and chair, to keep them from bedding in the tie.

My invention will involve but a slight expense, and may be easily applied, and will render the joint firm and secure. At the same time it will permit the ready removal of any one rail which may become broken or otherwise damaged, without any displacement of the adjacent rails, and it will also allow the rails to expand by heat and contract by cold.

Having thus described my invention, what I claim, and desire to secure by Letters Patent, is—

The combination, in a rail-joint, of the rails having in their meeting ends longitudinal coincident slots, the chair having side plates and a central rib, and made of a length equal to or less than one of the slots, and a filling-key placed through and secured in the longer slot between the chair and the rear wall of such slot, substantially as set forth.

In testimony that I claim the above I have hereunto subscribed my name in the presence to of two witnesses.

WILLIAM. S. THAYER.
